CANDLESTICK

Frederick W. Lindblad, 7 Hatherbury Court, Prestbury
Subdivision, Aurora, Ill. 60504

Filed Nov. 29, 1972, Ser. No. 310,382

Term of patent 14 years

Int. Cl. D26—01

U.S. Cl. D48—2

FIG. 1 is a front view of a candlestick showing my new design;

FIG. 2 is a top view thereof;

FIG. 3 is a fragmental cross sectional view taken on the line 3—3 of FIG. 2 with a portion of the base cut away for the purpose of disclosure; and

FIG. 4 is a bottom view thereof.

I claim:

The ornamental design for a candlestick, as shown and described.
